Design No. 4,078, dated May 31, 1870.

DESIGN FOR A TRADE-MARK.

The Schedule referred to in these Letters Patent and making part of the same.

We, GEORGE W. LANGHORNE, JOHN D. LANGHORNE, and NATHANIEL B. JOHNSTON, partners, under the firm and style of G. W. LANGHORNE & Co., of the city of Lynchburg, county of Campbell and State of Virginia, have invented and produced a new and original Design for a Trade-Mark, of which the following is a specification.

Our design consists of a card or label having in the center the picture of a woman on a deer, holding in her right hand an arrow and tobacco-pipe, and above it, in letters, the words "Westward Ho!". Beneath these, and separated from each other by the figure of the woman, are the words "Smoking Tobacco;" and immediately to the right of the center picture the words "Manufactured by;" also, below the center picture the words "G. W. Langhorne & Co., Lynchburg, Va."

Claim.

We claim, as our joint invention—

The design for a trade-mark, as described and shown.

GEORGE W. LANGHORNE.
